UNITED STATES PATENT OFFICE

JAMES BARELS, OF CHICAGO, ILLINOIS

CONTAINER

Application filed April 7, 1928. Serial No. 268,241.

This invention relates to containers in general and specifically though not exclusively to containers such as oil cans.

Several attempts have been made to provide an oil can which could be easily manipulated to pour oil therefrom without spilling the oil or having it leak about sides and top of the can, but as far as I am aware no can has ever been provided which will overcome all of these deficiencies.

The oil can embodying the present invention is particularly adaptable for home use, or in private garages or other places where a small quantity of oil can be stored, and which will permit ready access to the can and allow a steady constant flow of oil without spilling or otherwise making the can unhandy to handle. While the present invention has been designed primarily for carrying and storing small supplies it may be made in any size desired and used for any purpose whatever.

The primary object of the invention is to provide a can equipped with a self-contained movable spout whereby the oil in the can may be easily and efficiently poured from the can without spilling any of the oil.

Another object is to provide a can which will permit the oil to be poured therefrom without gurgling or splashing, and which permits the oil to be poured from the can in a constant steady even flow.

A further object is to provide a new and novel arrangement of parts for drawing all the fluid from the can by merely tilting the can on a stand provided therefor, whereby the fluid will flow regularly through a novel spout arranged on the can.

And a still further object is to provide a can having a novel air vent arranged in a particular fashion within the can whereby air may enter the can to replace the oil which has been poured therefrom.

The particular can embodying the invention is particularly adapted to be used in conjunction with the can and stand which is disclosed and claimed in my co-pending application Serial No. 268,242 filed concurrently herewith.

50 The accompanying drawings illustrate a

selected embodiment of the invention and the views are as follows:

Fig. 1 is a side elevation partly in section showing the can in tilted or pouring position and embodying the invention.

55

Fig. 2 is a vertical sectional view of the can in normal or upright position.

Fig. 3 is a top plan view.

Fig. 4 is a detail sectional view showing my improved spout and air vent, with the spout in normal or non-operating position.

Fig. 5 is a similar view showing the spout in operating or pouring position.

Fig. 6 is plan sectional view on the line 6—6 of Fig. 5.

65

Fig. 7 is a detail plan view of the spout in reected or non-operating position.

Fig. 8 is a detail plan view showing the spout in a modified form.

Fig. 9 is a detail perspective view of the modification shown in Fig. 8.

Referring to the drawings 10 designates generally a can having a top 11 provided with an intake 12, a discharge 13 and a handle 14. The intake 12 may be provided with a cap 75 or seal 15 which is applied when the can is filled, and the discharge may be provided with a threaded cap 16. The can may be provided with outstanding pins 17 and 18 which engage a stand 19 whereby the can may be 80 tilted at any desired angle to pour the oil therefrom. The pins and stand are clearly shown and described in the aforesaid co-pending application and form no part of the present invention except in the combination 85 herein shown.

A casting or member 20 is fixed in the cutlet 13 as clearly shown in Figs. 4 and 5, and this member is provided with an aperture 21 extending therethrough which receives a 90 tube or pipe 22 for providing an air vent to the inside of the can at a point opposite the discharge or outlet.

The tube has an upstanding end 23 where it enters the member 20 and this end is preferably made flush with the top of the member 20 as shown at 24, and is fastened to the top of the can as by solder 25. Through this medium air is supplied to the inside of the can to take the place of the oil which is being 100

poured therefrom thus assuring a constant steady flow of oil.

A spout 26 is arranged in an opening 27 formed in the member 20. This spout is 5 tapered and curved as shown and has sliding movement in the opening. The smaller end 28 of the spout is the outlet end and the larger end 29 is inflow end, as is usual in spouts of the conventional type. An integral 10 annular flange or collar 30 is arranged on the end 29 of the spout and it is adapted to seat against the inside of the member 20 when the spout is out to make a tight connection with the member 20 and prevent oil from seeping 15 between the outer wall of the spout and the inside wall of the member 20. This collar also prevents the spout from slipping through the opening and out of the can. The opening 27 is also tapered so that when the 20 spout is pulled out to pouring position it will snugly engage the wall surrounding the opening and further prevent any oil from escaping around the outside of the spout.

The spout is preferably made round in cross 25 section, and to prevent the spout from turning in the opening and to maintain it in proper position, a flange or fin 31 is formed on the upper side thereof which engages a recess or slot 32 formed in the member 20, 30 Figs. 6 and 7. A lug or handle 33 is formed on the end 28 of the spout to allow the spout to be easily withdrawn to operating position, and to prevent the spout from falling into the can when it is in receded or inoperative 35 position.

The upper side of the member 20 inclines downwardly and inwardly as at 34 so that any oil which may be on the spout can flow back into the can.

40 In Figs. 8 and 9, I have shown a spout 35 which is rectangular in cross section and which slides in a rectangular opening 36 formed in a casting or member 37. This spout may be provided with a fin 38 which engages a slot 39 in the member 37, Fig. 8. However, if the diagonal dimension of the outer end of the spout 35 is greater than the regular inside width of the opening 36, there is no chance of the spout being turned in the 45 opening and hence no fin will be required. The spout 35 is provided with a collar 40 at its lower or larger end which seats against the inner side of the member 37 for the same purpose as described relative to the collar 30. 50 The spout 35 is tapered in the same manner as the spout 26 and for the same purpose. An air vent 41 similar to the vent 22 is fastened in the member 37 as shown.

The use of my invention will stimulate the 60 storage of oil in small quantities, such as five or ten gallon lots, by private automobile owners and others, as the can is easily operated and the disadvantages inherent in conventional cans are eliminated. My improved 65 can may be easily refilled, or the can may

be returned to the dealer and a filled can of like construction can be given in return, plus the cost of the oil. Also, both the openings may be sealed by the dealer or refiner so that each time the customer receives a can of oil 70 he knows he has received the kind of oil marked on the can and not some substituted low grade oil. My improved can is very simple in construction, efficient and positive in operation, and may be manufactured at a 75 very low cost.

Throughout the specification I have used the term oil as applying to the liquid contained in my improved container but it is to be understood that I am not limited to this 80 specific use as liquid of any kind may be used in the container with like or greater success.

I am aware that changes in the form, construction and arrangement of the parts may be made without departing from the spirit of 85 the invention or sacrificing any of the advantages thereof and I reserve the right to make all such changes as fairly fall within the scope of the following claims.

I claim:

1. A container having an opening therein, a member arranged in said opening and having a slot and a plurality of apertures therein, a spout slideable in one of said apertures, means to limit the sliding movement of said 95 spout, and means on said spout and engaging said slot to prevent revoluble movement of said spout.

2. A container having an opening therein, a member arranged in said opening and having a slot and a plurality of apertures therein, a spout slideable in one of said apertures, a collar on one end of said spout, and a handle on the other end, a fin on said spout and engaging said slot to keep said spout from 100 turning, and a tube in the other of said apertures and leading to the interior of said container to provide a vent, said collar and said handle limiting the slideable movement of 105 said spout.

JAMES BARELS.
